UNITED STATES PATENT OFFICE.

GEORGE E. SEIDEL, OF RICHMOND, INDIANA.

NASAL MEDICATOR.

SPECIFICATION forming part of Letters Patent No. 746,749, dated December 15, 1903.

Application filed March 18, 1903. Serial No. 148,284. (No model.)

To all whom it may concern:

Be it known that I, GEORGE E. SEIDEL, a citizen of the United States, residing in the city of Richmond, in the county of Wayne and State of Indiana, have invented certain new and useful Improvements in Nasal Medicators, of which the following is a specification, which when taken in connection with the accompanying drawings, forming a part thereof, is sufficiently clear and concise as to enable others skilled in the art to which it appertains to make and use the same in its preferred and modified construction.

My present invention does not contemplate a radical reconstruction of the constituent elements of devices of this character, but rather the adaptation of old principles with the mechanical elements reduced to their simplest proposition and as a natural sequence accentuating the utilitarian residual benefits thereof and adapting them to serve the highest economic ends.

The object of my invention, broadly speaking, is the provision of a syringe, insufflator, atomizer, sprayer, injector, or inhaler consisting of a mechanical composite of tested instrumentalities or concatenations or tantamount devices for directing a medicament into or upon the nasal passages and organs and the plexus constituting the respiratory system.

Another object of my invention is the provision of a nasal medicator consisting of simple mechanical propositions correlated into a consonant ensemble for the expeditious insertion of aeriform or gaseous medicants to the pituitary or mucous membrane, the meatuses, the ramifications of the olfactory nerves, and contiguous and sympathetic organs thereof.

Another object is the provision of a merciful nasal medicator apposite to the amplitude of its various requirements, incontestably subserving the highest economic ends as a natural sequence to the germanic synthesis of the mechanical construction and the intermutuality of utilization.

Still another object is the provision of a nasal medicator for the insertion of medicaments or douches of either a liquid, powder, or gaseous constituent into the nasal passages for the purpose of a douche, equoration,

or medicament; and, finally, another object is the provision of a new article of manufacture, a nasal medicator consisting of a minimum of mechanical parts adapted to obtain a maximum of efficiency and which can be manufactured and sold at a comparatively low price.

Other objects and advantages of my invention will appear from the drawings, from the description set forth otherwheres in this specification, and from the claim hereunto appended.

With the above-named objects in view my invention consists in the form, construction, and arrangement of the several elements with reference to each other and the specific attachments with the interstinctive parts intermutually combined and in the legitimate combinations of the several parts with reference to each other and to the entire invention.

Referring now to the drawings by the indicated figures, Figure 1 is an isometrical view of my entire invention, showing one manner of application. Fig. 2 is a central longitudinal section of same. Fig. 3 is a modified form of my invention, showing a different manner of application and use.

In the drawings similar indices refer to and denote similar parts throughout the several views.

I will now describe my invention in detail, which I will state as briefly and compactly as I may.

In the drawings the indice A represents the mouth, and B the nose, of an individual.

The indice C represents a receptacle which I design shall contain a medicament—such, for instance, as a menthol or the like.

The indice D represents the upper converging end of the receptacle C, which is adapted for insertion in the nostrils of the patient. The lower end of the receptacle C is formed open, with a bushing or gasket E, formed of cork or soft rubber, adapted to fit therein, and a central opening is provided through the bushing E to receive and hold the large end of the fitting G. The fitting G is preferably formed U-shaped, with a central opening therethrough of same general contour thereof. The large end of said fitting is adapted to be inserted in the opening

in the bushing E and the opposite or small end to receive the lower end of the flexible tube H. In the upper end of the flexible tube H is inserted a mouthpiece I, with a central opening therethrough.

F represents a medicament contained in the receptacle, and it should be of a porous or granular formation in order that it may be penetrated by a forced draft, and K and L represent the upper and lower dams, respectively, to retain the medicament in place. Small openings are formed through the said dams in an axial direction to allow the air to pass through the space inclosed thereby.

15 For use the medicament—such, for instance, as menthol—is placed in the receptacle C and secured between and by the dams K and L, and the parts of the invention are otherwise assembled substantially as shown in Fig. 2. 20 The point D is then placed to or in one of the nostrils of the nose B, and the mouthpiece I is placed between the lips of the mouth A, and the air is then exhaled from the lungs through the opening in the mouthpiece I, the 25 flexible tube H, the fitting G into the interior of the receptacle C, where the air becomes charged with the medicament in its passage therethrough and is forced through the nostril and the meatuses to the pituitary 30 or mucous membrane, where the medicament is desired to be effective and which by the ordinary method of inhaling the medicated air would pass beyond said parts and enter the lungs of the patient.

35 In some instances I find it advisable to modify my device to a construction on the order of a medicinal insufflator or atomizer, in which case I replace the U-shaped fitting G with a straight or L-shaped fitting M, thus 40 extending the flexible tube H below and parallel with the receptacle C, as shown in Fig. 3, and to the lower end of the tube H, I secure the fitting P, providing means whereby a rubber ball O may be connected thereto, 45 and on the opposite side of the ball O is a valve N, connected with the interior of the ball. By this modified arrangement it will be apparent that air may be pumped into the receptacle C by alternately contacting and 50 releasing the ball O, drawing the air in through the valve N, and forcing it through the medicament and thence into the nostrils and accomplishing mechanically the same results as hereinbefore stated in regard to the 55 method of application.

It is apparent that the fitting G instead of being U-shaped, as shown, may, if desired, be made L-shaped, only requiring a small additional length of the tube H, but making 60 the fitting more easy of manufacture.

By the use of my improved construction, substantially as herein shown and described, I have indubitably produced a device of simple construction and when expeditiously applied with the medical ingredients will accel-

erate the cure of the nasal and its sympathetic organs.

The simplicity of my invention, together with its positiveness of action and effectiveness of the resultant operation, will appeal 70 to any one familiar with the treatment of nasal and kindred diseases, and while I am aware that devices of a somewhat similar character have been constructed, yet in my opinion they all, more or less, lack that positiveness of action and adaptation and inter-mutual relationship of the several elements 75 which should be a vital characteristic of devices of this kind, and, in my opinion, the crux of the whole matter lies more particularly in what has been the inability heretofore of conducting the medicament to the exact spot to be treated and to allow the flow to be controlled instantly at the will of the patient. This I have accomplished in the construction herein shown and described.

My invention is perfectly adapted to accomplish the results for which it is intended, and it is evident that changes in and modifications of the specific construction herein 90 shown and described may be made and that analogous parts may be used to accomplish the same results without departing from the spirit of my invention or sacrificing any of its many advantages, and the specific 95 construction of the details of my invention, in which novel features are embodied, may be variously changed without altering the essential principles of the invention which are claimed as new.

Having now fully shown and described my invention and the best means for its construction and operation to me known at this time, what I claim as new, and desire to secure by Letters Patent of the United States, 105 is—

In a nasal medicator, the combination, a medicament-receptacle provided with an upper converging end and a lower open end, a bushing fitted in the lower end of the receptacle, a U-shaped fitting with an opening therethrough, one end of said fitting being inserted in the opening in bushing and the other end of the fitting being inserted into the lower end of a flexible tube, the flexible tube connected to said fitting and to a mouthpiece, the mouthpiece connected to the upper end of said flexible tube with a central opening connecting therewith, a pair of perforated dams disposed some distance apart in said receptacle and containing a medicament therebetween, all substantially as shown and described.

In testimony whereof I have hereunto signed my name to this specification in the 125 presence of two subscribing witnesses.

GEORGE E. SEIDEL.
